CLAIM

The ornamental design for an oval shaped foam pump actuator, as shown and described herein.

DESCRIPTION

FIG. 1 is a front perspective view of the oval shaped foam pump actuator, showing my new design, with the nozzle shown in the open position;

FIG. 2 is a rear perspective view of thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a right side view thereof; and

FIG. 8 is a left side view thereof.

FIG. 9 is a front perspective view of the oval shaped foam pump actuator, showing my new design, with the nozzle shown in the closed position;

FIG. 10 is a rear perspective view of thereof;

FIG. 11 is a top plan view thereof;

FIG. 12 is a bottom plan view thereof;

FIG. 13 is a front elevation view thereof;

FIG. 14 is a rear elevation view thereof;

FIG. 15 is a right side view thereof; and,

FIG. 16 is a left side view thereof.

The broken lines are for environmental purposes only and form no part of the claimed design.
